KNITTING MACHINE

Frank G. Weisbecker, Glenside, Pa., assignor to
 Hosiery Patents Incorporated, Lansdale, Pa., a
 corporation of Pennsylvania

Application March 7, 1942, Serial No. 433,807

6 Claims. (Cl. 66—82)

This invention relates to improvements in knitting machines and more particularly to improvements in the needle bar motion of a straight knitting machine, such as the conventional straight machine for knitting full-fashioned hosiery.

Straight knitting machines usually comprise a relatively large number of knitting sections. Many machines now in use have as many as 28 knitting sections, and some machines have as many as 40 knitting sections. Each of these knitting sections is adapted to knit a separate blank or part thereof, so that a multi-section machine simultaneously produces as many separate blanks or parts thereof as the machine has knitting sections. The knitting sections of a machine are relatively arranged in what may be termed an end to end relation. These multi-section machines present a number of problems because of their size, their complex mechanism, and the precision required in their operation. Certain of these problems relate to the needle bar motion of the machine. This motion comprises the knitting needles of the machine and the means for operating these needles.

It is, therefore, an object of this invention to provide an improved needle bar motion for straight knitting machines.

Another object is to provide an improved needle bar motion for a multi-section, full-fashioned hosiery, straight knitting machine, whereby the operation of the knitting needles will be substantially smoother and more accurate than the operation provided by conventional needle bar motions.

Still another object is to provide a needle bar motion with improved mechanism for supporting and operating the knitting needles.

A further object is to provide a novel guide for a needle bar of a straight knitting machine and thereby secure more accurate operation of the knitting needles.

Another object is to provide needle operating mechanism which minimizes the possibility of temperature changes materially affecting needle operations.

Other objects and advantages of this invention will be apparent and readily understood from the following description, the appended claims, and the accompanying drawings which illustrate a preferred embodiment of the invention.

Referring now to the drawings,

Figure 1 is a front elevational view of part of

a straight knitting machine embodying this invention.

Figure 2 is a cross-sectional view taken on line 2—2 of Figure 1.

Figure 3 is a detail view of part of the mechanism illustrated in Figure 1.

Figure 4 is an elevational view on enlarged scale of part of the mechanism shown in Figure 1.

Figure 5 is an exploded view to illustrate the relationship of certain parts of the mechanism illustrated in Figures 1, 2 and 4.

In Figure 1, there is illustrated a set of two knitting sections which may be and preferably is duplicated throughout an entire machine. For example, the machine may have twenty-four knitting sections or twelve of the sets of sections illustrated in Figure 1. As these sets are duplicates and it is impractical to illustrate in one figure a complete machine of, for example, twenty-four sections, it is sufficient to show and describe only one set of knitting sections. This disclosure will enable one to understand fully the invention when practiced throughout a multi-section machine.

The knitting sections are supported by the machine frame which comprises a plurality of longitudinal and transverse frame members. Figures 1 and 2 show one of the longitudinal frame members at 10, and Figure 1 shows

two of the transverse frame members 11. The longitudinal frame members may be of conventional form and are rigidly connected to the transverse frame members according to the usual practice. The transverse

frame members 11 are preferably spaced apart to accommodate a set of two knitting sections between each two adjacent transverse frame members. A twenty-four section machine, for example, would, therefore, have thirteen of the trans-

verse members 11 to support the twelve sets of knitting sections.

Each knitting section of the machine includes a conventional sinker bed 12 which is rigidly secured to the longitudinal frame member 10.

This sinker bed 12 is clearly illustrated in Figure 5 and is usually of integral or one-piece, cast construction including at each end thereof an integral depending leg-like member 13 (see Figure 5) forming part of a split bearing, which will be described more fully hereinafter. The two split bearings at the opposite ends of each sinker bed 12 support a conventional knockover bit assembly 14 including a series of knockover bits 16 (see Figure 2).

Each of the sinker beds 13 is provided with a

series of sinkers and dividers (not shown) which are of conventional construction and operate in known manner. A series of needles 17 (Figure 2) is positioned opposite each sinker bed 12 and operates in known manner in the spaces between the sinkers and dividers (not shown) and the spaces between the knockover bits 16.

Needle operating mechanism

According to this invention, each series of needles 17 is supported in a separate needle bar 18, there being a separate needle bar 18 for each knitting section. Each of the needle bars 18 is pivotally supported on a set of two lifter arms 19.

A separate needle bar shaft 21 is provided for each set of two knitting sections and is preferably of such length that its opposite ends terminate in bearings 22 carried by the two transverse frame members 11 (see Figure 1) adjacent the opposite ends of the respective set of knitting sections. Figure 1 shows one complete needle bar shaft 21, and also the adjacent ends of two needle bar shafts 21 for corresponding sets of knitting sections (not shown). The adjacent ends of two adjacent needle bar shafts 21 may be journaled in the same bearing 22 as illustrated in Figure 1 and are preferably spaced apart to receive a felt lubricating washer 23 therebetween. Each bearing 22 may have an opening 24 therein to receive a supply of lubricating material for the washer 23.

Each of the separate needle bar shafts 21 supports two sets of lifter arms 19 and is, therefore, adapted to operate two separate needle bars 18. Each lifter arm 19 has an integral collar or sleeve 26 (Figure 1) which is adjustably secured to its supporting needle bar shaft 21 by means of a set screw 27.

Each needle bar shaft 21 derives its motion from cam shaft means comprising a main cam shaft 28 and cam 29. For this purpose, a cam lever 31 is operatively secured to each needle bar shaft 21 by means of a set screw 32. Each cam lever 31 may have a cam follower or roller 33 for engaging the periphery of the cam 29 and a spring 34 to yieldingly maintain the cam roller 33 in engagement with the cam 29.

The lifter arms 19 are preferably such that they have an effective length of greater dimension than the effective length of the cam lever 31. That is, the distance from the pivotal axis of the connection between the needle bar 18 and its lifter arms 19 to the axis of the needle bar shaft 21 is greater than the distance from the axis of the needle bar shaft 21 to the axis of the cam roller 33. In this way, it is possible to provide humps or rises on the cam 29 of substantially less height than the rises on conventional cams. Figure 3 shows in dotted lines the rises on a conventional cam 36 and also shows a cam 29 in full lines according to this invention and with substantially smaller rises. By reducing the size of the cam humps or rises, a much smoother and more uniform operation is secured during needle bar movements.

Spring arms 37 (Figures 1 and 2) are provided for engagement with the needle bars 18 as the latter approach the desired limit of movement in the downward direction. These spring arms 37 oppose any tendency of the needle bars 18 to exceed their intended limit of travel in their downward motion. The spring arms 37 also assist in providing smoother and more uniform action of the needle bar 18 as it approaches its lower limit of travel and reverses its direction of

movement. If desired, two spring arms 37 may be provided for each needle bar 18 and supported at one end by the longitudinal frame member 10 as shown in Figures 1 and 2. Each spring arm 37 is preferably so positioned that its outer, free end will engage the respective needle bar 18 when the latter has covered about three-quarters of the distance in its normal downward travel.

Any suitable means may be provided for rock-
10 ing the needle bars 18 about their pivotal connec-
tions with their lifter arms 19. An arm 38
(see Figure 3) may be rigidly secured to each
15 needle bar 18 and is adapted to be operated from
the cam shaft 28. The knitting operations of
the needles 17 may be in accordance with well-
known and conventional practice.

As each set of two knitting sections has a
10 separate needle bar motion according to this in-
vention, each set operates independently of the
20 others and will not be affected by varying condi-
tions in any needle bar motion other than its
own.

Needle bar guide

Each of the separate needle bars 18 during its
25 operation is maintained in alignment with its
respective sinker bed 12 by guide means accord-
ing to this invention. By maintaining the proper
30 alignment between each needle bar 18 and its
sinker bed 12, the proper relation and spacing
35 between the needles 17 and the sinkers (not
shown), dividers (not shown) and knockover bits
16 is obtained at all times during the knitting
operations. This result is important, as it avoids
breakage of sinkers, dividers, knockover bits and
needles due to improper operation of the needles
and consequent collision of these fragile machine
parts.

It is also a definite advantage to secure the
40 needle bar guide means to the sinker bed 12 as
this construction also opposes any tendency of
the sinker bed 12 to move endwise and get out of
alignment with its respective needle bar 18.

Each of the needle bar guide means may com-
45 prise a guide element, set screw or stud 41
threaded into a bracket-like member 42 and se-
cured in adjusted position by a lock nut 43. The
set screw 41 preferably has a head 44. This head
50 44 has a flat face to act as a stop to endwise
movement of the respective needle bar 18 toward
55 the corresponding set screw 41. One of these
guide means is preferably arranged at each end
50 of each needle bar 18 with the respective set
screw 41 so adjusted that its head 44 is slightly
55 spaced from the adjacent end of the needle bar
18. This spacing, for example, may be on the
order of one to four thousandths of an inch.
60 Each guide means is also preferably such that its
set screw head 44 is opposite the adjacent end of
the respective needle bar 18 during its entire
cycle of operations, that is during its raising and
65 lowering movements by the lifter arms 19 and its
rocking movements toward and away from the
sinker bed 12 by means of the arm 38.

Each of the needle bar guide means is pref-
65 erably secured rigidly to a sinker bed 12. In the
event, the guide means is to be applied to a
70 machine already in use, the detachable halves
or caps 46 of the split bearings carried by the
sinker beds 12 may each have a groove 47 cut
75 or otherwise formed therein as shown in Figure
5. This groove 47 may be cut in the side of the
bearing part 46 opposite to the side facing the
sinker bed leg-like member 13. If desired, the
bracket-like member 42 and the bearing part

46 may be made in the form of a single part or cast as one-piece.

Each leg-like member 13, its detachable bearing part 46, and the corresponding bracket-like member 42 are preferably provided with aligned openings for receiving two screws or threaded elements 48 and 49 (as clearly illustrated in Figure 5). Each of the screws (48 and 49) extends through the member 42 and the bearing part 46 and is threaded into the corresponding opening in the corresponding leg-like member 13 to secure rigidly these three parts (42, 46 and 13) in assembled relation. The outer ends of the openings in bracket-like member 42 for receiving the screws 48 and 49 are preferably enlarged to receive the screw heads as clearly shown in Figure 5.

In the preferred and illustrated embodiment of this invention, it will be noted that endwise movement of each needle bar 18 in either direction is arrested by a set screw 41 and that the needle bars 18 are somewhat shorter in length than the distance between the leg-like members 13, which carry the above described needle bar guide means. The spacing between the adjacent ends of each two adjacent needle bar shafts 21 is preferably somewhat greater than the spacing between the needle bars 18 and their respective guides or set screws 41. Endwise movement of the needle bar shafts 21 in their bearings 22 is controlled by the cooperation between the needle bars 18 and their above described guide means.

The foregoing is to be understood as illustrative, as this invention includes all modifications and embodiments coming within the scope of the appended claims.

I claim:

1. In a multi-section straight knitting machine, the combination comprising a rigid frame of longitudinal and transverse frame members, two of said transverse frame members being relatively spaced to provide for only a set of two knitting sections therebetween, a sinker bed for each of said two knitting sections and secured to said rigid frame, the improvement comprising a needle bar shaft having its opposite ends supported by said two transverse frame members and a cam lever operatively connected to said shaft for actuating the same, needle bar means associated with said sinker beds, lifter arms operatively connecting said shaft and said needle bar means, and guide means rigidly secured to said sinker beds and positioned to arrest endwise movement of the needle bar means and thereby maintain proper alignment between said sinker beds and said needle bar means during knitting operations.

2. In a multi-section straight knitting machine, the combination comprising a rigid frame of longitudinal and transverse members, two of said transverse frame members being relatively spaced to provide for only a set of two knitting sections therebetween, a sinker bed for each of said two knitting sections and secured to said frame, the improvement comprising a needle bar shaft having its opposite ends terminating in said two transverse frame members and journaled therein, a cam lever operatively connected to said shaft for actuating the same, two sets of lifter arms operatively connected to said shaft, a separate needle bar operatively connected to each set of said lifter arms and positioned opposite one of said sinker beds, said needle bars being adapted to be lifted and lowered by said arms during operation of said shaft, means for

rocking said needle bars relative to said lifter arms, and means to arrest endwise movement of said needle bars and maintain said needle bars in alignment with said sinker beds, said arresting means being rigidly secured to said sinker beds.

3. In a multi-section straight knitting machine, the combination comprising a rigid frame of longitudinal and transverse members, two of said transverse frame members being relatively spaced to provide for only a set of two knitting sections therebetween, a sinker bed for each of said two knitting sections and secured to said frame, the improvement comprising a needle bar shaft having its opposite ends terminating in said two transverse frame members and journaled therein, a cam lever operatively connected to said shaft for actuating the same, two sets of lifter arms operatively connected to said shaft, a separate needle bar operatively connected to each set of said lifter arms and positioned opposite one of said sinker beds, said needle bars being adapted to be lifted and lowered by said arms during operation of said shaft, means for rocking said needle bars relative to said lifter arms, and separate guide means for each of said needle bars, each guide means being rigidly secured to the sinker bed opposite the needle bar guided thereby and being adapted to maintain the needle bar in alignment with the corresponding sinker head during needle bar movements.

4. In a multi-section straight knitting machine having a rigid frame of longitudinal and transverse frame members, the transverse frame members being relatively spaced to provide for a set of two knitting sections between each set of two transverse members, a cam shaft journaled in said frame, and a sinker bed for each knitting section and rigidly secured to a longitudinal frame member, the improvement comprising: a separate and independent needle bar motion for each set of two knitting sections, each of said motions including a separate needle bar shaft having the opposite ends thereof journaled in the transverse frame members for the corresponding set of two knitting sections, a cam lever operatively connected to said needle bar shaft and actuated by said cam shaft, two sets of lifter arms carried by said needle bar shaft, and a separate needle bar for each knitting section, each needle bar being operatively connected to a set of said lifter arms for movement thereby and relative to its respective sinker bed during actuation of said cam lever; a bracket-like member rigidly secured to each end of each of said sinker beds; and an element adjustably carried by each of said bracket-like members and positioned opposite an end of the corresponding needle bar for guiding said needle bar during said needle bar movement, whereby each needle bar is maintained in proper alignment with its respective sinker bed.

5. In a multi-section straight knitting machine having a rigid frame of longitudinal and transverse frame members, the transverse frame members being relatively spaced to provide for a set of two knitting sections between each set of two transverse members, cam shaft means mounted in said frame, and a sinker bed for each knitting section and secured to said frame, the improvement comprising: a separate and independent needle bar motion for each set of two knitting sections, each of said motions including a separate needle bar shaft having the opposite ends thereof terminating in and supported by

the transverse frame members for the corresponding set of two knitting sections, a cam lever operatively connected to said needle bar shaft and actuated by said cam shaft means, a set of lifter arms for each knitting section and carried by said needle bar shaft, and a separate needle bar for each knitting section and operatively connected to the corresponding set of lifter arms.

6. In a multi-section straight knitting machine having a rigid frame of longitudinal and transverse frame members, the transverse frame members being relatively spaced to provide for a set of two knitting sections between each set of two transverse members, cam shaft means mounted in said frame, and a sinker bed for each knitting section and secured to said frame, the improvement comprising: a separate and inde-

pendent needle bar motion for each set of two knitting sections, each of said motions including a separate needle bar shaft having the opposite ends thereof terminating in and supported by the transverse frame members for the corresponding set of two knitting sections, a cam lever operatively connected to said needle bar shaft and actuated by said cam shaft means, a set of lifter arms for each knitting section and carried by said needle bar shaft, and a separate needle bar for each knitting section and operatively connected to the corresponding set of lifter arms, the effective length of said lifter arms being of greater dimension than the effective length of said cam lever.

FRANK G. WEISBECKER.
